LIQUID MIXING MACHINE

Mark King Wilson, Chattanooga, Tenn.

Application July 18, 1938, Serial No. 219,842

7 Claims. (Cl. 259—56)

My invention relates to liquid mixing machines, and more particularly to such machines for mixing bottled liquids in the case.

An object of the invention is to provide a machine which is so constructed as to receive, handle, and deliver cases of bottled liquids efficiently and with a minimum of effort and operations to be performed by the operator.

Another object is to provide novel stop means for retaining the case in the machine for mixing, which, while being initially movable manually to permit the starting of a case into or out of the machine, will be held in retracted position by the case until cleared by the case, when the stop means will automatically advance to operative position.

A further object is the provision of means for adjusting the top of the carriage of the machine to different elevations to accommodate cases of different sizes.

Another object is to provide novel means for imparting rotary and oscillating motion to the carriage of the machine for mixing, and for stopping and releasably retaining the carriage in normal position.

Other objects will appear hereinafter.

The invention consists in the features, combination and arrangement of parts hereinafter described and particularly pointed out in the claims.

Referring to the drawings,

Figure 1 is a partial cross sectional view of a machine embodying my invention, taken substantially on the line 1—1 of Fig. 2.

Fig. 2 is a side elevation of the machine.

Fig. 3 is a sectional detail view of the connection of the crank lever to the driving shaft.

Fig. 4 is the opposite side elevation of the machine.

Fig. 5 is a sectional detail view similar to a portion of Fig. 1 showing a modified construction of drive in which the carriage of the machine is rotated through a complete revolution.

Fig. 6 is a partially sectional view through the locking mechanism for the stop means as seen in Fig. 2.

Fig. 7 is an enlarged, partially sectional elevation through the top member of the carriage showing the locking pins.

Fig. 8 is a sectional plan view through the crank lever stop which holds the carriage of the machine in normal position.

In the drawings, 11 and 12 represent side plates of the carriage of a liquid mixing machine embodying my invention which carriage is designed

to receive a case of bottled liquids for mixing the liquid therein. The side plates are desirably secured at their lower portions to the side members 14 of the carriage, as by means of rivets 62 or the like, and cross bar members 25 permanently connect the side plates at their upper ends. Cross members 66 of the carriage extend between and may be attached to the side members 14 of the carriage, as by means of bolts 65. Roller members 13 extend between the side members 14 of the carriage and provide the case receiving and supporting surface.

The member 14 at one side of the carriage is provided with a main drive shaft 67 secured thereto by pin 16, and having a bearing in the bearing bracket 48 which is attached to the channel side support 1 by means of rivets or bolts 49. The side member 14 at the opposite side carries shaft 15 secured thereto by pin 16 and the shaft has bearing in bearing bracket 17 which is attached to the channel support 2 by means of rivets or bolts 18. The outer end of the shaft 67 has secured thereto by pin 51 a small crank arm 50. A pin 47 on the outer end of crank arm 50 is engaged by a connecting link 25 which at its other end engages a pin 45 carried by the gear 43. The gear 43 is keyed at 44 to a shaft 42 received in bearing bracket 40 attached to support member 1 by means of rivets 41.

A drive gear 68 meshes with the gear 43 and is keyed at 92 (Fig. 3) to a shaft 91 having bearing in bracket 93 secured to support 1 as by means of rivets 95.

The main driving crank lever 52 is desirably 35 pivotally attached to the shaft 91, as by means of pin 75, to permit of swinging movement of the crank lever from and toward the machine, and angular motion of the crank outwardly being limited by means of a pin 76 engaging a 40 part of the machine. The outer end of the crank lever 52 is provided with a handle, preferably having a sleeve which is free to revolve about the handle pin 69.

A crank lever stop is provided at 39 secured to 45 support 1 as by means of rivets 89 and has projecting lugs 90 between which crank 52 enters to hold the crank and the carriage controlled thereby in normal position. The normal position of the carriage is desirably substantially horizontal and 50 that of the crank arm is desirably substantially vertical when in engagement with the stop 39.

To the carriage at the opposite side plate 12 thereof is secured a bearing bracket 19, as by means of rivets 20. A bearing pin 21 is secured 55

to the part 19 and a bell crank lever member 22 is mounted to rotate on the pin 21. Lever arms or links 59 and 60 are attached to the crank member 22 by means of pins 23, and at their opposite ends are attached to arms 58 by means of pins 61. Arms 58 are secured to shaft members 54 which extend across the carriage and are rotatably mounted in the side members 14, collars 57 being desirably provided at the ends 10 of the shafts 54 opposite to the crank arms 58. Secured to the intermediate portion of the shafts 54 are stop brackets 55 carrying stop pins or members 56.

The crank arms 58 are desirably disposed to 15 extend in substantially opposite directions from their shafts 54, when the stop members 56 are disposed in upright or advanced position, as shown in Fig. 2, to that upon their simultaneous actuation upon movement imparted to the bell crank 20 22 about the bearing 21, the stop members are moved by swinging in unison on their shafts 54 toward or from advanced or operative position.

Secured to crank member 22 is a handle lever 28 having a ball end 80. A plate 30 is rigidly 25 mounted on lever 28 and has lugs 31 extending therefrom and providing supports for a pin 82 on which is pivoted a latch or locking member 29 having an end 83 for engaging in hole 84 extending through plate 12 and a reinforcing plate 24 30 secured to plate 12, to lock the parts with the stops 56 in advanced or operative position. The opposite end of the latch 29 is disposed adjacent the ball end 80 of the lever 28, so that it is actuated upon grasping of the ball end of the lever 35 to release the lever for operation to retract the stops 56. A spring 81 engages between the latch 29 and plate 30 urging the latch to engage its end 83 into the opening 84. A stop abutment 32 is mounted on the plate 24 and against which the 40 latch member 29 contacts to limit the movement of the lever 28 at its locking position. A spring 63 is secured between the plate 30 of the lever 28 and a member 64 on the carriage to urge the lever to such position advancing the stops 56.

45 A removable top member for the carriage is provided by a plate member 34 desirably having upstanding flanges provided by a rectangular angle iron frame 33 secured to the member 34. Beneath the plate 34 is secured a fiber plate 35 by 50 means of rivets 36. A pin 26 is secured at each end of the upstanding flange of the top member 33, and at the opposite side of the top member is provided a plunger 37 at each end, having a spring 38 for urging the plunger outwardly. The plunger 55 37 is slidably mounted in aligned openings in frame 33 and an inner bearing bracket 86. A stop collar 87 is attached to plunger 37 by pin 88 and serves to limit outward movement of the plunger. A pin 85 is secured to the inner end of the plunger to serve as an operating handle. The plungers 37 and pins 26 are adapted to be 60 adjustably and removably disposed in a series of openings 27 in the side plates 11 and 12 of the carriage to adjust the top member to accommodate cases or containers with bottles of different size. The rows of holes 27 are desirably staggered to provide a fine adjustment.

70 The side supports 1 and 2 of the machine are each adjustably supported in a channel base support 3 mounted on an angle iron base 8 having base plates 9. Braces 4 are preferably provided between the base 8 and supports 3. Braces 5 are provided between the supports 1 and 2. Holes 10 are provided in supports 1 and 2 to align adjustably with holes in the members 3, bolts 6 with

nuts 7 being provided to extend through the aligned holes to secure the supports 1 and 2 in adjusted elevation to the members 3.

In the operation of the machine, the top member 5 of the carriage is adjusted so that the fiber board lining on its under side is disposed adjacent the top of the case or package containing the liquid, desirably with a slight clearance of from $\frac{1}{4}$ " to $\frac{1}{2}$ ". The stop control lever is then moved away from its stop against the action of its spring, which causes the stops 56 to swing below the plane of the top of the rollers 13. A full case of bottled liquid may then be started into the machine, as from a conveyor disposed on a level with the rollers 13, the bottom of the case passing over the stops 56. The stop control lever may then be released and the weight of the case holds the stop members down until the rear of the case passes over the rear stop, when the spring on the stop control pulls the lever back to the locked position which raises the stops at each end simultaneously and prevents the case from running out at the forward or delivering end of the carriage, and also definitely retains the case in position during mixing.

The operator then turns the crank lever which is desirably geared to the drive means by a one to two gear and the cam or link and crank mechanism causes the carriage containing the goods to move from a horizontal position through an arc, which desirably may be about 150 degrees. At this point, as indicated in dotted lines in Fig. 4, with the crank still turning in the same direction, the cam gear, or link and crank mechanism, reverses the machine and returns it through the same arc back to the horizontal position of the carriage. A decided mixing effect laterally is obtained by the reversing or oscillating movement. The goods are oscillated as many times as may be required for thorough mixing of all the ingredients. The machine may then be locked in the horizontal position of the carriage by allowing the crank to drop into the slot in member 39. The stop control lever is moved to retract the stops 56 and the case of mixed goods is removed from the machine preferably onto a delivery conveyor not shown. The control lever may be released as soon as the forward end of the bottom of the case has engaged over the depressed stop, and the lever and stops will return to locked position under action of the spring, as soon as the case is discharged from the machine. If, however, another case has been started into the carriage, the lever and stops will not return automatically to position until the said case has cleared the stops 56.

In Fig. 5 is shown a modified construction of drive mechanism in which the carriage is to be turned in complete revolutions of 360 degrees in the same direction as long as the crank lever is turned. The main shaft in Fig. 5 is indicated by the numeral 71, and which is fastened to the side member 14 by means of pins 16 and to the gear 73 as by means of a key 74, the shaft rotating in a bearing bracket 94 secured to support 1 as by rivets 71. A shaft 70 also rotates in bearing bracket 94 and carries gear 72 and is driven by crank lever 52 through a pin 75. The crank stop 79 is indicated as attached to the member 1 as by rivets 78. The operation of this complete rotary form of machine embodying my invention is similar to that of the oscillating rotary type hereinbefore described, the crank lever 52 being initially swung slightly outwardly to clear the recess in the stop member, and then rotated in

one direction until sufficient desired mixing has been obtained, whereupon the crank 52 is returned to position within the slot in the stop member with the carriage in normal substantially horizontal position.

While the invention is particularly adapted for mixing bottled liquids in the case, it is not to be restricted thereto, as liquid in bulk in containers may be mixed in the machine, and modifications may be made in the structure as described without departing from the invention as defined in the appended claims.

I claim:

1. In a liquid mixing machine, a carriage open at its ends for receiving and delivering a container having therein the liquid to be mixed, said carriage comprising side walls, means forming a bottom for said carriage and extending between and connecting the side walls, means extending between said side walls at the upper portion thereof, and an adjustable top member for said carriage adjustable to different elevations to accommodate containers of varying height received within said carriage, said top member comprising a plate having vertically disposed flanges, pin means in said flanges, and a plurality of openings in the walls of the carriage for selectively receiving said pin means, said pin means comprising a stationary pin in the flange at one side of said top member, and a pin member mounted for sliding movement in the flange at the opposite side of said top member, and a spring urging said slidable pin outwardly.

2. A liquid mixing machine comprising a pivotally mounted carriage open at its ends for receiving a box or case containing liquid to be mixed, fed to one end of said carriage, and to be delivered from the opposite end thereof, following movement about said pivot for mixing, and stop means at each open end of the carriage adjacent the bottom thereof forming the case receiving surface, and means rendering said stop means movable in unison to position them above the ends of said case supporting bottom surface in case obstructing position or below the ends of said case supporting bottom surface out of case obstructing position, said stop means being carried on transversely disposed rod mounted at each open end of the carriage for pivotal movement.

3. A liquid mixing machine comprising a pivotally mounted carriage open at its ends for receiving a box or case containing liquid to be mixed, fed to one end of said carriage, and to be delivered from the opposite end thereof, following movement about said pivot for mixing, and stop means at each open end of the carriage adjacent the bottom thereof forming the case receiving surface, said stop means at each end being supported on transverse rods for pivotal movement, and means rendering said stop means movable in unison to position them above the ends of said case supporting bottom surface in case obstructing position or below the ends of said case supporting bottom surface out of case obstructing position, said last named means including a lever pivoted on said carriage and connecting links between said lever and transverse rods to move the stop means in unison by movement of said lever.

4. A liquid mixing machine comprising a pivotally mounted carriage open at its ends for receiving a box or case containing liquid to be mixed, fed to one end of said carriage, and to be delivered from the opposite end thereof, following movement about said pivot for mixing, and stop means at each open end of the carriage ad-

jacent the bottom thereof forming the case receiving surface, said stop means being mounted for pivotal movement on transversely disposed rods at each end of the carriage, and means including a lever pivoted on said carriage, and connecting links between said lever and transverse rods to move the stop means in unison by movement of the lever, to position the stop means above the ends of said case supporting bottom surface in case obstructing position or below the ends of said case supporting bottom surface out of case obstructing position, a fixed stop on the carriage, said lever being spring urged toward said fixed stop to a position advancing said stop means, and latch means releasably retaining said lever in such position.

5. A liquid mixing machine comprising a pivotally mounted carriage open at its ends for receiving a box or case containing liquid to be mixed, fed to one end of said carriage, and to be delivered from the opposite end thereof, following movement about said pivot for mixing, and stop means at each open end of the carriage adjacent the bottom thereof forming the case receiving surface, said stop means being mounted for pivotal movement on transversely disposed rods at each end of the carriage, and means including a lever pivoted on said carriage, and connecting links between said lever and transverse rods to move the stop means in unison by movement of the lever, to position the stop means above the ends of said case supporting bottom surface in case obstructing position or below the ends of said case supporting bottom surface out of case obstructing position, a fixed stop on the carriage, said lever being movable toward said fixed stop to advance said stop means, a latch pivoted to said lever adjacent the handle end thereof, and spring urged into locking engagement with a portion of the carriage when engaging said fixed stop, said latch retaining said lever in such position until released by grasping the handle of the lever and latch.

6. A liquid mixing machine comprising a pivotally mounted carriage open at its ends for receiving a box or case containing liquid to be mixed, fed to one end of said carriage, and to be delivered from the opposite end thereof, following movement about said pivot for mixing, and stop means at each open end of the carriage adjacent the bottom thereof forming the case receiving surface, and means rendering said stop means movable in unison to position them above the ends of said case supporting bottom surface in case obstructing position or to position them in a retracted position below the ends of said case supporting bottom surface out of case obstructing position, said stop means being so disposed in retracted position as to be engaged by the bottom of the case in passing thereover, and to be held in retracted position by the case until the bottom of the case has passed out of engagement with the said stop means.

7. A liquid mixing machine comprising a pivotally mounted carriage open at its ends for receiving a box or case containing liquid to be mixed, fed to one end of said carriage, and to be delivered from the opposite end thereof, following movement about said pivot for mixing, and stop means at each open end of the carriage adjacent the bottom thereof forming the case receiving surface, said stop means being mounted for pivotal movement on transversely disposed rods at each end of the carriage, and means including a lever pivoted on said carriage, and connecting

links between said lever and transverse rods to move the stop means in unison by movement of the lever, to position the stop means above the ends of said case supporting bottom surface in a case obstructing position or to position them in a retracted position below the ends of said case supporting bottom surface out of case obstructing position, said stop means being movable by said

lever to said retracted position, and being so disposed in said retracted position as to be engaged by the case in passing thereover, and to be held in retracted position by the case until the bottom of the case has passed out of engagement with the ⁵ said stop means.

MARK KING WILSON.
